CLAIM

The ornamental design for a cleansing cloth with pattern, as shown and described.

DESCRIPTION

FIG. 1 is a perspective view of a cleansing cloth with pattern showing our new design;

FIG. 2 is a top view of the cleansing cloth with pattern as shown in FIG. 1;

FIG. 3 is a bottom view of the cleansing cloth with pattern as shown in FIG. 1;

FIG. 4 is a right side view of the cleansing cloth with pattern as shown in FIG. 1;

FIG. 5 is a left side view of the cleansing cloth with pattern as shown in FIG. 1;

FIG. 6 is a front side view of the cleansing cloth with pattern as shown in FIG. 1; and,

FIG. 7 is a back side view of the cleansing cloth with pattern as shown in FIG. 1.

The broken lines in the drawings depict the boundaries of the claimed design and form no part thereof.
